Primary Examiner — John A Voytek(74) *Attorney, Agent, or Firm* — Dickinson Wright PLLC(57) **CLAIM**

The ornamental design for a tire, as shown and described.

DESCRIPTION

FIG. 1 is a side elevation view of the tire of my design; FIG. 2 is a side elevation view of the tire of my design, taken from the opposite side of that shown in FIG. 1; and, FIG. 3 is an enlarged, partial view of the tire of our design, taken from FIG. 1.

The dash-dot-dot-dash lines define the boundaries of the claim. The broken line disclosure in the drawings depicts environmental subject matter forming no part of the claimed design. The design elements are co-planar with the tire sidewall.
